UNITED STATES PATENT OFFICE.

FRANK F. LEWIS, OF JANEVILLE, WISCONSIN, ASSIGNOR TO LEWIS KNITTING COMPANY,
OF JANEVILLE, WISCONSIN.

BIFURCATED GARMENT.

No. 913,741.

Specification of Letters Patent.

Patented March 2, 1909.

Application filed April 9, 1908. Serial No. 426,051.

To all whom it may concern:

Be it known that I, FRANK F. LEWIS, of Janesville, in the county of Rock and State of Wisconsin, have invented certain new and 5 useful Improvements in Bifurcated Garments; and I do hereby declare the following to be a full, clear, and exact description of the invention, such as will enable others skilled in the art to which it appertains to 10 make and use the same.

My invention relates to an improvement in bifurcated garments, such as union suits of underwear and similar garments designed for wear about the trunk, hips and thighs.

15 The object of the invention is to provide a bifurcated garment with a falling seat portion formed continuous with the main portions of the garment, and with this object in view the invention consists in certain features of construction and relative arrangement of parts as will hereinafter be described and pointed out in the claims.

In the accompanying drawings, Figure 1 is a view in rear elevation of a bifurcated 25 garment embodying my improvement. Fig. 2 illustrates a detached view of the legs and falling seat sections, and Fig. 3 is a detached view of the seat gusset.

1 represents the main body of the garment 30 which may be made of tubular knitted or flat knitted fabric in the usual manner and of any desired material. The back portion 2 of the trunk or body portion is extended downwardly from the shoulders to the 35 length desired for the shirt portion, its lower end being indicated by the dotted line 3, 4.

The back portion of the lower part of the garment is composed of the two main pieces 5, 6, illustrated in Fig. 2, which are united to 40 the front portion by the usual outer and inner leg seams 7, 8. The usual diamond shaped seat gusset 9 may or may not be inserted at the crotch as desired, and the inner edges 10, 11, of the back pieces 5, 6, are 45 brought together and united thus forming the vertical back seam 12, of the falling seat portion 13, which latter, when the garment is worn is drawn up over the lower end of the shirt portion and about the seat and hips of 50 the wearer and is secured in place by buttons 14, at or near the waist line or any other suitable means for detachably secur-

ing the falling seat in place may be employed. By bringing together the edges 10 and 11 of the pieces 5—6 and uniting them, it insures 55 the desired fullness to the falling seat portion without the usual extension of the seat gusset and the undesirable seams attending such construction. This construction also results in narrowing the width of the falling 60 seat flap at its top and consequently fewer buttons or other devices are required to detachably secure it to the main body of the garment.

The above results are due to the shape of 65 the edges 10 and 11 of the pieces 5 and 6, which are so constructed and shaped as to diverge and diagonally cross the wale of the fabric of the pieces 5 and 6 in such manner that when both pieces are sewed together 70 above the forks at edges 10 and 11 to form the flap or drop seat the wale of the fabric composing the upper portions of the pieces 5 and 6 shall converge to said vertical back seam 12, and be in a line diagonal to the wale 75 of the fabric of the back portion 2, Fig. 1.

Having fully described my invention what I claim as new and desire to secure by Letters-Patent, is;—

1. A garment of the class described having 80 a drop seat made continuous with the rear leg portions, the upper portions of the latter having diagonal edges drawn together and united thereby forming a drop seat of the desired fullness said drop seat being narrower at its point of attachment to the body at the waist line than at the seat line, substantially as set forth.

2. A garment of the class described, having 90 a drop seat made continuous with the rear leg portions, the portions above the seat fork being so shaped that when drawn together and secured by a vertical seam, the rib or wale of the fabric of such portions above the seat fork shall converge to the 95 said vertical seam so uniting them, substantially as set forth:

In testimony whereof, I have signed this specification in the presence of two subscribing witnesses.

FRANK F. LEWIS.
